UNITED STATES PATENT OFFICE

FREDERICK W. COFFING, OF PERRYSVILLE, INDIANA

AUXILIARY CROSS ARM POLE CLAMP

Application filed August 18, 1930. Serial No. 475,962.

This invention relates to a device for changing cross arms.

The chief object of this invention is to provide a temporary support for a cross arm or a temporary cross arm, detachably supported on a pole to which the wires supported by the cross arm to be replaced are temporarily secured or supported during the changing from the original to the replacing cross arm.

The chief feature of the invention consists in the particular construction of the cross arm supporting base and the detachable mounting therefor upon a pole.

15 The full nature of the invention will be understood from the accompanying drawings and the following description and claim:

In the drawings, Fig. 1 is a side elevational view of one form of temporary cross arm 20 associated with the cross arm support showing the same applied to a pole, the latter being shown dotted.

Fig. 2 is an enlarged top plan view of the cross arm support and pole mounting mechanism, the pole being shown dotted.

Fig. 3 is a front view of a cross arm support and pole clamping lever.

Fig. 4 is a side elevation of the attachment, including the auxiliary cross arm and showing 30 the same mounted upon a pole, the latter being shown in elevation.

In the drawings 10 indicates a pole and 11 a cross arm. Means for temporarily mounting the cross arm on a pole includes a supporting portion which is clampingly mounted on said pole.

The base portion of the aforesaid supporting means includes a partially cylindrical portion 12, which is provided at its parallel edges with two outwardly and oppositely directed wings 13 and 14. Wing 14 is notched at 15 and said notch or groove is defined by a pair of parallel flanges 16, apertured as at 17 to receive a pivot form of a bolt or the like 18. The wing 13 is suitably apertured as at 19 and an eye-bolt 20 is supported thereby and supports one end of a link chain 21 or other flexible clamping construction. Link chain 21 is adapted to have any one of its 50 links associated with the hook portion 22 of

a hook link member 23, which has a curved portion 24 and passes over the pin 18 as a fulcrum. The other end of the hook terminates in an eye 25 which is pivoted as at 26 upon a lever having the bifurcated ends 27 which straddle the eye portion 25 and said lever terminates in a handle portion 28. After the handle is tilted counterclockwise, see Fig. 2, and the chain link is associated with the hook portion 22 with substantially all of the slack taken from the chain, then clockwise movement of the lever 28 upon the pivot 18 will cause the chain and partially cylindrical portion 12, to clampingly engage the pole 10.

The upper end of the wings 13 and 14 and the upper edge of the partially cylindrical portion 12, terminate in a transverse plate 30 which is practically divided into two portions by the partially cylindrical portion. See 70 Fig. 2.

Likewise, illustrated in said figure, is an upstanding wall 31, integral with the plate 30 at its bottom edge and which is tangential to the projected cylindrical surface of the partially cylindrical portion 12. Reinforcing webs 32 insure rigidity of the wall construction. The wall is also provided with a suitable number of openings 33 and 34. The cross arm 11 is supported by the wall portion and in substantially tangential relation to the pole. See Fig. 4. Herein the temporary or auxiliary cross arm 11 includes a plurality of hooks 40, arranged in spaced relation and if desired, the cross arm may include pivoted end portions, as at 41, pivoted at 42 and normally retained in cross arm aligned position by suitable manually engageable latches 43, or when released therefrom, said portions 41 may be positioned as shown in the left hand portion of Fig. 1. In this position, portion 41 and the hooks 40 thereon, are adapted to support a number of superposed wires, while when positioned as shown in the right hand of Fig. 1, the cross arm is arranged to support five wires positioned in substantially horizontal alignment.

The invention claimed is:—

In a pole attachment, a relatively wide ar- 100
cuate plate conforming to a portion of the

circumference of the pole, a wing at each end of said plate coextensive with said ends and disposed substantially in the same plane with each other, a cross arm attaching wall of appreciable length and integral with the upper side of said plate tangential with the latter and substantially parallel with said wings, webs connecting the upper portions of the wings with the lower edges of the wall, and a lever operated flexible retaining member associated with said wings for detachably holding the plate to said pole; the relation of the plate and cross arm attaching wall being such that said wall or an arm carried thereby does not interfere with operation of the lever.

In witness whereof, I have hereunto affixed my signature.

FREDERICK W. COFFING.
